J. HOGAN

RAILROAD CHAIR AND PLATE

Filed Aug. 30, 1923

Inventor:
James Hogan,
Chas. E. Riordon

Att'y.

UNITED STATES PATENT OFFICE.

JAMES HOGAN, OF CENTRALIA, PENNSYLVANIA.

RAILROAD CHAIR AND PLATE.

Application filed August 30, 1923. Serial No. 660,199.

To all whom it may concern:

Be it known that I, JAMES HOGAN, of Centralia, in the county of Columbia and State of Pennsylvania, a citizen of the United States, have invented certain new and useful Improvements in Railroad Chairs and Plates, of which the following is a specification.

The present invention contemplates a construction for joining adjacent ends of rails and includes web engaging plates so fastened as to permit movement of the parts resulting from expansion and contraction.

Other objects of this invention include, with the above arrangement, means for elevating the wheels of cars above the joint to prevent the noise resulting from engagement therewith; the provision of guide means for engagement with the wheel to prevent lateral movement; the use of a projection on one of the clamping plates for spacing the ties and the provision of tie plates arranged with perforations for the reception of the fasteners so spaced as to co-operate with the clamping members.

The above objects are carried out by providing the clamping plates with elongated registering openings which correspond to openings in the adjacent ends of rails for the reception of bolts, the elongated openings permitting the movement of the bolts and consequent movement of the rail ends under expansion and contraction.

Numerous other novel features will appear by reference to the accompanying drawings forming a part of this specification and wherein like numerals of reference designate corresponding parts throughout the several views in which:

Figure 1 is a top plan view:

Figure 2 is a side elevation:

Figure 3 is an end view:

Figure 4 is a section on line 4—4 of Figure 1, and

Figure 5 is a perspective view of the tie plate.

Referring now more in detail to the drawings, the ends of adjacent rail sections are illustrated by reference characters 1 and 2, and are shown secured together by means of the present invention including the outer clamping plate 3 and the inner plate 4. Both of these plates are formed with elongated bolt slots 5 through which the bolts 6 pass and are held by the usual nuts and washers 7.

The outer plate 3 projects inwardly to snugly engage the web of the rail ends and is formed with the curved tread portion 8, the central portion of which is arched above the tread surface of the rails. This tread portion 8 of the outer plate 3 also tapers inwardly toward the rail ends, the taper diminishing gradually from the center and terminating at approximately the extremities of the flange 9. The flange 9 which is adapted for engagement with the outer face of the wheels projects upwardly from the outer edge of the top of the plate 3 and is gradually of increasing thickness to a point approximately the center. The outer face of the flange 9 is flush with the outer face of the plate. By this construction, a gradual engagement with the wheels is had by the flange. Extending laterally from the bottom of the plate 3 is the flange 10 having the notches 11 spaced so as to be located over the ties, and downwardly from this flange 10 is the integral tie spacing block 12, which is located between the ties to prevent lateral movement of the latter. The inner plate 4 is formed with the web engaging portion 14 which corresponds to the web engaging portion of the outer plate. To prevent engagement with the wheel flanges the inner plate is grooved as at 15, and the ends of this groove merge into the curved cutaway portions 16 and 16' thus avoiding contact with the moving wheels. A flange 17 projects from the lower edge of the inner plate and notches 18 corresponding to the notches 11 on the plate 3 are provided.

For changing the pitch of the rails and to provide adjustable seating means, the tie plates 19 are utilized. These plates 19 gradually increase in thickness to form a wedge shaped body, shown more clearly in Figure 5, and are provided with spaced openings for the reception of the rail retaining spikes 20. It will be seen that the arrangement of these spike openings is such as to cause the spikes to engage the end walls of the notches formed in the flanges of the inner and outer plates and this arrangement limits lateral movement of the various parts.

To provide means for the spacing of the rail ends, in assembling the present device, a transverse opening 22 is formed in the outer plate 3. This opening may be of any desired shape and is located at the center of the plate so as to properly position the

joint. In use, a suitable tool of the desired thickness is inserted in this opening to project between the rail ends and is withdrawn when the rails are properly locked in adjusted position.

From the foregoing it will be obvious that the present invention provides means not only for the expansion and contraction of the rail ends but also forms a noiseless crossing including guide means for the passing wheels. Also, by the particular constructions and arrangement of the tie plates and the co-operating notches in the flanges an unusually firm and immovable joint is provided, all parts being secured with relation to one another without interference with the freedom of movement of the rail ends as heretofore mentioned.

What I claim as new and useful and desire to secure by Letters Patent is:—

1. A rail joint comprising in combination with the adjacent ends of rails having transverse openings, inner and outer clamping plates, one of said plates being formed with an elevated tread portion, a wheel guide carried by the plate, and tie spacing means.

2. A rail joint including in combination with adjacent rail ends having transverse openings, clamping plates formed with elongated bolt slots registering with said transverse openings, bolts projecting through the bolt slots and said openings, one of said plates being formed with a tapering tread portion, a guide flange adjacent said tread portion, and a guide groove carried by the other plate.

3. A rail joint including the adjacent ends of rails, plates clamped to said rail ends, a gradually elevated tread portion carried by one of said plates, a guide flange adjacent the tread portion tapering inwardly from its respective ends to a point approximately the apex of said tread portion, and a transverse opening formed in one of the plates to permit spacing of said rail ends.

4. A rail joint including a pair of clamping plates, one of said plates being formed with a curved tread portion, a guide flange

adjacent said tread portion having tapering extremities, a base flange formed with spaced elongated notches, a spacing block formed integral with said plate and projecting downwardly at a point approximately its center, and a guide groove formed in the other plate for engagement with a wheel flange.

5. In a device of the class described including in combination with adjacent rail ends, inner and outer clamping plates therefor, an arched tread portion carried by said outer plate, an upwardly projecting guide flange adjacent said tread portion having its outer face flush with the outer wall of said plate, a base flange formed with spaced notches, a spacing block projecting downwardly from said base flange at a point intermediate its length, a flange groove formed in the inner clamping plate, and means for permitting the spacing of said rail ends.

6. In a device of the class described including in combination with adjacent ends of rails, inner and outer clamping plates therefor, a wheel flange guide carried by one of said plates, and means provided by the other plate to permit the spacing of said rail ends.

7. In a device of the class described, including in combination with adjacent rail ends, clamping plates therefor, tie spacing means formed integral with one of said clamping plates, means for permitting the spacing of said rail ends, and tie plates having fastening means engaging said clamping plates.

8. A rail joint comprising an inner and an outer clamping plate, tie spacing means carried by one of said plates, and wheel guide means including a longitudinal groove formed in one of said plates and a flange carried by the tread of the other clamping plate, and fastening means for said clamping plates.

In testimony whereof I hereunto affix my signature.

JAMES HOGAN.
